UNITED STATES PATENT OFFICE

172,233

COMBINED BOTTLE OPENER AND CAN PUNCH

Samson J. Maland, Grafton, Wis.

Application August 7, 1953, Serial No. 26,351

Term of patent 14 years

(Cl. D44—29)

To all whom it may concern:

Be it known that I, Samson J. Maland, a citizen of the United States, residing at Grafton, Ozaukee County, State of Wisconsin, have invented a new, original, and ornamental Design for a Combined Bottle Opener and Can Punch, of which the following is a specification, reference being had to the accompanying drawing, forming a part hereof, in which:

Fig. 1 is a side view in elevation of a combined bottle opener and can punch showing my new design;

Fig. 2 is a top plan view thereof;
Fig. 3 is a bottom plan view thereof; and,
Fig. 4 is an end elevational view thereof.

I claim:

The ornamental design for a combined bottle opener and can punch, as shown.
